[57] CLAIM

The ornamental design for a pipe railing terminal fitting, as shown and described.

DESCRIPTION

FIG. 1 is a top view of one embodiment of a pipe railing terminal fitting of the present invention;

FIG. 2 is a rear view of the pipe railing terminal fitting of FIG. 1;

FIG. 3 is a side view of the pipe railing terminal fitting of the FIGS. 1 and 2, the opposite side view being a mirror image thereof;

FIG. 4 is a front view of the pipe railing terminal fitting of FIGS. 1-3;

FIG. 5 is a bottom view of the pipe railing terminal fitting of FIGS. 1-5;

FIG. 6 is a cross-sectional view taken along lines 6—6 of FIG. 3 to show the cross-sectional surface contour of the pipe railing terminal fitting of FIGS. 1-6;

FIG. 7 is a side view of the pipe railing terminal fitting of FIG. 3, showing a connector in broken lines for illustrative purposes only, and forms no part of the claimed design;

FIG. 8 is a top view of a second embodiment of a pipe railing terminal fitting of the present invention;

FIG. 9 is a rear view of the embodiment of FIG. 8;

FIG. 10 is a side view of the embodiment of FIGS. 8-9, the opposite side view being a mirror image thereof;

FIG. 11 is a front view of the embodiment of FIGS. 8-10;

FIG. 12 is a bottom view of the embodiment of FIGS. 8-11; and,

FIG. 13 is a cross-sectional view taken along line 13—13 of FIG. 10 to show the cross-sectional surface contour of the terminal fitting.
